UNITED STATES PATENT OFFICE

EDWARD S. CORNELL, JR., OF WATERTOWN, CONNECTICUT, ASSIGNOR TO THE CHASE COMPANIES, INCORPORATED, OF WATERBURY, CONNECTICUT, A CORPORATION

TUBE-Straightening-and-sizing-tool

Application filed February 10, 1931. Serial No. 514,779.

This invention relates to an improvement in tube-sizing-and-straightening tools and particularly to tools for straightening and sizing the ends of wrought-metal water-tubes, 5 etc., though its use is not so limited.

It may be stated at the outset of this description that when the ends of tubing become distorted through accident or rough handling and an effort is made to bring the 10 same back to form by means of a mandrel forced into its interior, though the tube will respond to such treatment, it will not, except on rare occasions, assume its original cylindrical form for the reason that unless the 15 mandrel be larger than the original interior size of the tube, it will be found that local stretching has been caused and that certain portions of the tube-wall will remain out of contact with the mandrel, a situation which 20 is avoided by the use of the novel straightening-and-sizing tool described herein.

The main object of this invention is to provide a simple and convenient tool of the class referred to which will effectively restore the 25 end portion of a water-tube or the like to commercially perfect form.

With the above and other objects in view as will appear from the following, my invention consists in a tube-straightening-and-sizing tool having an outer sleeve-portion for engagement with the exterior surface of the terminal end of a tube and a coaxial mandrel-portion for engagement with the interior surface of the terminal end of a tube; the said 30 coaxial sleeve- and mandrel- portions being of different internal and external diameters respectively to provide an annular tube-receiving space therebetween.

My invention further consists in a tube-straightening-and-sizing tool characterized as above and having certain other details of construction and combinations of parts as will be hereinafter described and particularly recited in the claims.

45 In the accompanying drawing:

Fig. 1 is a side view of a tube-straightening-and-sizing tool embodying my invention;

Fig. 2 is an end view thereof;

Fig. 3 is a transverse sectional view taken 50 on the line 3—3 of Fig. 1;

Fig. 4 is a longitudinal sectional view taken on the line 4—4 of Fig. 2;

Fig. 5 is a view corresponding to Fig. 4 but showing the action of the tool as the same is being forced into the distorted end of a 55 tube to straighten the same; and

Fig. 6 is a transverse sectional view taken on the line 6—6 of Fig. 5.

In the embodiment herein chosen for the illustration of my invention, I employ a tube-straightening-and-sizing tool consisting of a cup-shaped outer member 10 having a cylindrical sleeve-portion 11 and a bottom-wall 12, which latter is formed with a threaded axial bore 13 for the reception of the externally-threaded shank 14 of a mandrel-member 15. The said mandrel-member is provided at its inner end with a shoulder 16 seating against the adjacent face of the bottom-wall 12 of the cup-shaped outer member 10, 60 as clearly shown in Figs. 4 and 5 of the drawing.

The outer end of the mandrel-member 15 projects beyond the end of the outer member 10 and is conically tapered as at 17 to facilitate its entry into the terminal end of a tube 18 (Fig. 5). The forward inner corner of the sleeve-portion 11 of the outer member 10 is also provided with an outwardly-flaring conical taper 19 for the engagement and inward deflection of the outer corner 20 of the tube 18 or the like.

As herein shown, the mandrel-member and the outer member of my improved straightening-and-sizing tool are shown as separately formed, which is done for convenience of manufacture, though if desired, the parts may be integral.

My improved tool is preferably driven into the end of a tube by means of a mallet or the like. Now in the event that the tube being straightened and sized is so badly distorted as not to be completely restored by the mandrel-member 15, as is the case with the particular tube shown in Figs. 5 and 6, then the outwardly-flared conical taper 19 of the sleeve-portion 11 of the outer member will accomplish what the mandrel has failed to completely do, and will complete the restora- 90 95 100

tion of the end of the tube to commercially accurate form and size.

Preferably and as shown in the drawing, the straight body-portion 21 of the mandrel-member 15 extends beyond the point at which 5 the taper 19 of the sleeve-portion 11 starts so that the mandrel-member completes its task before the end of the tube engages with the said conical surface 19. It is obvious 10 without further illustration that the parts may be proportioned to come into full play at one and the same time, or the parts may be so proportioned that the conical surface 19 comes into play before the tapered terminal 17 of the mandrel, but the proportioning 15 of the parts as shown in the drawing in this respect is preferred.

It will be understood by those skilled in the art that my invention may assume varied 20 physical forms without departing from my inventive concept and I, therefore, do not limit myself to the specific embodiment herein chosen for illustration, but only as indicated in the appended claims.

25 I claim:

1. As a new article of manufacture, a tube-straightening-and-sizing tool having an outer sleeve-portion for engagement with the exterior surface of the terminal end of a tube; and a coaxial mandrel-portion having a tapered terminal for engagement with the interior surface of the terminal end of a tube; the said coaxial sleeve- and mandrel-portions being adapted for operation as a unit 30 in fixed relation to each other, and the mandrel-portion being of less external diameter throughout than the internal diameter of the sleeve-portion, to provide an annular tube-receiving space therebetween.

40 2. As a new article of manufacture, a tube-straightening-and-sizing tool having an outer sleeve-portion for engagement with the exterior surface of the terminal end of a tube; and a coaxial mandrel-portion for engagement 45 with the interior surface of the terminal end of a tube; the said coaxial sleeve- and mandrel-portions each having a tapered tube-deflecting surface and being adapted for operation as a unit in fixed relation to each other, and the mandrel-portion being 50 of less external diameter throughout than the internal diameter of the sleeve-portion, to provide an annular tube-receiving space therebetween.

55 3. As a new article of manufacture, a tube-straightening-and-sizing tool having an outer sleeve-portion provided with a flaring deflecting-surface for engagement with the exterior surface of the terminal end of a tube; and a coaxial mandrel-portion having a tapered terminal for engagement with the interior surface of the terminal end of a tube; the said coaxial sleeve- and mandrel-portions being adapted for operation as a unit in 60 fixed relation to each other, and the mandrel- 65

portion being of less external diameter throughout than the internal diameter of the sleeve-portion, to provide an annular tube-receiving space therebetween.

4. As a new article of manufacture, a tube-straightening-and-sizing tool having an outer sleeve-member for engagement with the exterior surface of the terminal end of a tube; and a separately-formed mandrel-member arranged coaxially within and in fixed relation to the said sleeve-member for engagement with the interior surface of the terminal end of a tube; the said coaxial sleeve-member and mandrel-member each having a tapered tube-deflecting surface and being of different internal and external diameters respectively to provide an annular tube-receiving space therebetween. 70 75 80

5. As a new article of manufacture, a tube-straightening-and-sizing tool having a cup-shaped sleeve-member for engagement with the exterior surface of the terminal end of a tube, said sleeve-member having a bottom-wall; and a separately-formed mandrel-member arranged coaxially within the said cup-shaped sleeve-member and fixed relatively to the bottom-wall thereof for engagement with the interior surface of the terminal end of a tube; the said coaxial sleeve-member and mandrel-member being of different internal 90 95 and external diameters respectively to provide an annular tube-receiving space therebetween. 85 90

6. As a new article of manufacture, a tube-straightening-and-sizing tool having a cup-shaped sleeve-member for engagement with the exterior surface of the terminal end of a tube, said sleeve-member having a bottom-wall; and a separately-formed mandrel-member arranged coaxially within the said 100 cup-shaped sleeve-member and fixed relatively to the bottom-wall thereof for engagement with the interior surface of the terminal end of a tube; the said coaxial sleeve-member and mandrel-member each having a 105 tapered tube-deflecting surface and being of different internal and external diameters respectively to provide an annular tube-receiving space therebetween. 110 115

7. As a new article of manufacture, a tube-straightening-and-sizing tool having an outer sleeve-portion for engagement with the exterior surface of the terminal end of a tube; and a coaxial mandrel-portion for engagement 120 with the interior surface of the terminal end of a tube; the said coaxial sleeve- and mandrel-portions each having a tapered tube-deflecting surface, and the mandrel-portion being of less external diameter throughout than the internal diameter of the sleeve-portion, to provide an annular tube-receiving space therebetween; the starting points 125 of the tapered tube-deflecting surfaces of the sleeve-portion and mandrel-portion respec- 130

tively staggered to cause the same to act successively.

8. As a new article of manufacture, a tube-straightening-and-sizing tool having a tube-engaging end and comprising an outer sleeve-portion for engagement with the exterior surface of the terminal end of a tube; and a coaxial mandrel-portion for engagement with the interior surface of the terminal end of a tube; the said coaxial sleeve- and mandrel-portions each having a tapered tube-deflecting surface, and the mandrel-portion being of less external diameter throughout than the internal diameter of the sleeve-portion, to provide an annular tube-receiving space therebetween; the starting point of the tapered tube-deflecting surface of the said mandrel-portion being nearer the tube-engaging end of the tool than the tapered tube-deflecting surface of the said sleeve-portion to cause the former to first come into play.

In testimony whereof, I have signed this specification.
